United States Patent Office

Des. 184,314
Patented Jan. 27, 1959

184,314

LUMINAIRE

Donald E. Husby, Fairview Park, and Edmund L. Izzi,
Cleveland, Ohio, assignors to Westinghouse Electric Corporation, Pittsburgh, Pa., a corporation of Pennsylvania

Application August 21, 1957, Serial No. 47,471

Term of patent 14 years

(Cl. D48—31)

Fig. 1.

Fig. 2.

Fig. 3.

Fig. 4.

Figure 1 is a top plan view of a luminaire showing our new design;

Fig. 2 is a view in side elevation thereof;

Fig. 3 is an end elevational view taken from the left of Fig. 2; and

Fig. 4 is an end elevational view taken from the right of Fig. 2.

The dominant features of the luminaire design are shown by solid lines.

We claim:

The ornamental design for a luminaire, as shown and described.
